W. H. L. DONALDSON.
AIR CLEANER.
APPLICATION FILED JULY 11, 1916.

1,286,250.

Patented Dec. 3, 1918

Inventor: William H. L. Donaldson,

Attorney.

UNITED STATES PATENT OFFICE.

WILLIAM H. L. DONALDSON, OF ST. PAUL, MINNESOTA.

AIR-CLEANER.

1,286,250.

Specification of Letters Patent.

Patented Dec. 3, 1918.

Application filed July 11, 1918. Serial No. 244,474.

To all whom it may concern:

Be it known that I, WILLIAM H. L. DONALDSON, a citizen of the United States, residing at St. Paul, in the county of Ramsey and State of Minnesota, have invented new and useful Improvements in Air-Cleaners, of which the following is a specification.

My invention relates to improvements in air cleaners for internal combustion engines.

10 As is well known, large quantities of dust find their way into the carbureter and cylinders of gas engines and this is particularly the case where these engines are used in tractors, for agricultural work, or on thoroughfares carrying much traffic. The effect of the dust is to rapidly decrease the efficiency of the carbureter and of the piston action, and ultimately to ruin the compression.

20 The object of my invention is to simply, efficiently and economically remove the solid matter from the air used in internal combustion engines.

25 A further object is to provide an air cleaner with numerous intake ports and corresponding distributing means so as to reduce the velocity of the entering air without impairing the suction through the carbureter.

30 A more detailed statement of its objects will appear in the following specification and claims.

35 The best embodiment of my invention now known to me is illustrated in the accompanying drawings, in which:

35 Figure 1 is an elevation of my device with the casing partly broken away; Fig. 2 is a plan view with the cap partly broken away; Fig. 3 is a section on the line 3—3 of Fig. 1 looking toward the top of the device; Fig. 4 is an enlarged detail of a portion of the annular distributing plate carried by the cap, and Fig. 5 is a section on the line 5—5 of Fig. 4.

45 My air cleaner comprises a cap A, a casing B in the form of a truncated cone, surrounding the separation chamber, and a dust collector C adapted to be removably threaded into the base of the casing.

50 The cap A is provided centrally at its top with a pipe 10 communicating at one end with the interior of the cleaner and at the other end with the intake of a carbureter (not shown). A pendant annular distributing plate 11 is formed upon or attached to the cap A and is so placed as to extend into the casing B and provide a peripheral air

passage between said plate and the casing B. This annular plate 11 is crimped to form a plurality of internal, curved, diagonal channels 12 and between these channels arcuate 60 openings 13 are cut through the plate with the flaps 13 formed by the cuts protruding outward.

The casing B is provided near its top with a series of air influent openings 14 arranged close together about its periphery and the portions of the casing which are partially cut away to form these openings are bent inwardly at their free edges to form air guides 15, whose outer surfaces are curved 70 vertically, with their upper edges 16 forming substantially tangential lines with the internal peripheral surface of the casing. The casing B is united to the cap A by means of a peripheral flange 17 formed on 75 the upper edge of the casing and by opening the outer edge 18 of the cap about said flange 17. When so united it will be observed that the openings 14 and air guides 15 in the upper surface of the casing are 80 positioned around and spaced from the upper or imperforate portion of the annular plate 11 on the cap. The lower end of the casing B is open and is provided with a ring 20 formed with internal threads 21 adapted 85 to receive corresponding threads upon the upper end of the dust receptacle C. Above the ring 20 a baffle plate 22, which is substantially square in outline, is attached at its corners to the casing B and is bent upward at its center to form a sliding surface 90 for any dust which may accumulate thereon, the trend of said surface being toward the openings 23 formed between the baffle and the inner surface of the casing. 95

The dust receptacle C is preferably formed of glass so that the amount of dust, accumulated therein at any particular time, may be obvious by inspection and this dust receptacle is furnished at its upper edge with 100 threads 24 adapted to be screwed into the threads 21 in the ring 20 and, when so fastened, to form an air tight closure for the base of the casing B. When the receptacle A is filled with dust it may be unscrewed 105 and emptied.

In operation the intermittent suction produced by the gas engine draws air into the cleaner through the numerous ports 14, at comparatively low velocity but without 110 throttling the carbureter; the centrifugal movement of air being accentuated by the

form of the air guides 15, and any dust which may get inside the plate 11 is further directed downward and controlled by the diagonal channels 12 on the inner surface of said plate. During these movements the dust or other particles of solid matter constantly move toward and are thrown against the inner surface of the casing B and finally fall through the openings 23 into the dust 10 container C while the clean air, being lighter than the solid matter thus removed, tends to remain in the center of the casing and within the distributing plate 11, and is thence drawn through the pipe 10 into the carbureter. I have found by exhaustive tests that with this device all of the solid matter suspended in the air drawn through the ports 14, except a mere trace, is retained in the cleaner and because of the area of the 20 numerous air influent ports in the casing the air enters at comparatively low velocity and therefore with only the lighter particles of dust in suspension. This feature furnishes a distinct advantage over air cleaners having only one or a few restricted air intake ports.

Having described my invention, what I claim as new and desire to protect by Letters Patent is:

1. An air cleaner for gas engines comprising a cap provided with a dependent, annular distributing plate, crimped to form diagonal air channels, a conical casing perforated near its top to admit air therethrough, a dust settling chamber below said plate and a dust collector attached to the base of said casing.

2. An air cleaner for gas engines comprising a cap provided with a dependent annular distributing plate formed with internal, 40 diagonal, channels therein, a casing pro-

vided with a series of air intake ports arranged close together and extending around the upper periphery of said casing, an air guide adjacent to, and extending tangentially within reach of said air ports and a dust collector removably attached to the base of said casing.

3. An air cleaner for gas engines comprising a cap provided with a dependent annular distributing plate formed with internal, 50 diagonal, channels therein, a conical casing provided with a series of air intake ports arranged close together and extending through the upper periphery of said casing, an air guide adjacent to, and extending tangentially within each of said air ports said casing forming an annular circulating channel around said distributing plate, a dust settling chamber below said plate, and a dust collector removably attached to the base of said casing.

4. An air cleaner for gas engines comprising a cap provided with a dependent annular distributing plate formed with internal, 55 diagonal, channels therein, a casing provided with a series of air intake ports extending around the upper periphery of said casing and a dust collector removably attached to the base of said casing.

5. An air cleaner for gas engines comprising a cap provided with a perforated, dependent, annular, distributing plate formed with diagonal air channels therein, a conical casing perforated near its top to admit air therethrough, a dust settling chamber below said plate and a dust collector attached to the base of said casing.

Whereof, I have hereunto subscribed my name to this specification.

WILLIAM H. L. DONALDSON.

Copies of this patent may be obtained for five cents each, by addressing the "Commissioner of Patents, Washington, D. C."

Correction in Letters Patent No. 1,286,250.

It is hereby certified that in Letters Patent No. 1,286,250, granted December 3, 1918, upon the application of William H. L. Donaldson, of St. Paul, Minnesota, for an improvement in "Air-Cleaners," an error appears in the printed specification requiring correction as follows: Page 2, line 46, claim 2, for the word "reach" read *each*; and that the said Letters-Patent should be read with this correction therein that the same may conform to the record of the case in the Patent Office.

Signed and sealed this 31st day of December, A. D., 1918.

[SEAL.]

Cl. 183—90.

F. W. H. CLAY,
Acting Commissioner of Patents.
